[57] **CLAIM**

The ornamental design for a scratch brush handle, as shown and described.

DESCRIPTION

FIG. 1 is a front elevational view of a scratch brush handle embodying our design;

FIG. 2 is an end elevational view thereof as seen from the left of FIG. 1;

FIG. 3 is a top plan view thereof; and

FIG. 4 is a bottom plan view thereof; and,

FIG. 5 is a rear elevational view thereof.

The broken line showing of brush bristles in the drawings is for illustrative purposes only and forms no part of the claimed design.

The portions of the opposite side and right end of the article neither shown in the drawing nor described in the specification form no part of the claimed design.

The portion of the right end of the article neither shown in the drawing nor described in the specification forms no part of the claimed design.

1 Claim, 2 Drawing Sheets

FIG. 5.
